UNITED STATES PATENT OFFICE.

JAMES McC. COLEMAN, OF ST. LAMBERT, QUEBEC, CANADA

BRAKE-HEAD.

No. 920,434.

Specification of Letters Patent.

Patented May 4, 1909.

Application filed September 28, 1908. Serial No. 455,117.

To all whom it may concern:

Be it known that I, JAMES McCUTCHEON COLEMAN, a citizen of the United States of America, and resident of the town of St. Lambert, in the Province of Quebec, in the Dominion of Canada, have invented certain new and useful Improvements in Brake-Heads; and I do hereby declare that the following is a full, clear, and exact description 10 of the same.

The invention relates to improvements in brake heads, as described in the present specification and illustrated in the accompanying drawings that form part of the same.

15 The invention consists essentially in the novel arrangement and construction of parts whereby the hanger is locked in the brake head independently of the shoe fastening.

The objects of the invention are to avoid 20 the danger incident to the dropping of the brake beam and head due to the accidental removal of the hanger from engagement with said head and to provide a simple, cheap and secure locking device.

25 In the drawings, Figure 1 is a perspective view of the device showing the shoe partially in section. Fig. 2 is an enlarged vertical sectional view showing the fastening. Fig. 3 is a horizontal section of Fig. 2 through the 30 hanger recess.

Like numerals of reference indicate corresponding parts in each figure.

Referring to the drawings, 1 is the brake head here shown as of substantially shell 35 form having the sides 2 forming the T-shaped slot 3 and the inwardly extending lugs 4 and 5, said lugs having the central pin holes 6 therethrough and the lug 4 having the pin holes 7 therethrough between 40 the central pin hole and the ends of said lug.

8 is a recess in the sides 2 and the piece 9 extending across the brake head. The said 45 brake head is formed at the top end immediately above said recess 8, with the longitudinal recess 10 for the main pin and the holes 11 to each side of said longitudinal recess adjacent to the walls thereof through the uppermost wall of the recess 8, said holes 50 11 being in alinement with the holes 7.

12 is the shoe having the lug 13 depending from the inner side thereof into the space between the lugs 4 and 5; said lug 13 having the central hole 14 in alinement with the 55 central holes 6.

15 is the pin extending downwardly

through the longitudinal recess 10 in the head through the central holes 6 and the hole 14 in the lug 13.

16 is the hanger here shown as of U-shaped form and inserted in the recess 8 and supporting the brake head 1.

17 is a pin inserted in a hole 11 and extending downwardly into a hole 7, said pin having the head 18 and the turned over end 19 projecting beyond the lower side of the lug 4, thus locking the hanger in place and independently securing the same of the pin 15.

20 is the brake beam inserted in the T-shaped slot 3 and extending across to a similar brake head at the other wheel of the car.

It will be thus seen that it is quite impossible for the hanger to shake out from the recess 8 on the removal of the pin 15 and it is a very common occurrence for the said pin 15 to be removed, frequently by dishonest persons for the sake of the metal in the shoe, and it is to guard against the accidents liable to happen by the dropping of the brake beam and the shoe, that this hanger is effectually locked in as shown in the present invention.

The exact construction as described herein is not essential, for the pin locking in the hanger may be arranged otherwise, the salient feature being the introduction of a locking member, apart from the shoe fastening pin.

What I claim as my invention is:

1. A brake head, having a hanger hole laterally arranged to the rear of the shoe face 90 and an opening from said hole through said face, a hanger, and removable means for closing said opening secured independently of the shoe fastening.

2. A brake head, recessed from its face at 95 the back of the brake shoe; a hanger in said recess, and a pin independent of the shoe fastening and locking said hanger in said recess.

3. A brake head, having a hanger hole therethrough and an opening leading from 100 said hole to and through the face at the back of the brake shoe, a vertical U-shaped hanger having its closed end of suitable size to slide through said opening into said hole, and means for securely closing said opening apart 105 from the ordinary fastening of the shoe to the brake head and removable therefrom.

4. In a brake head, a body portion having a recess toward the upper end extending laterally therethrough and lugs projecting inwardly from the inner face, a shoe having a lug on the rear side thereof, a pin extending

through said head and shoe lugs, a pin extending through the uppermost wall of said recess and through one of said head lugs and suitably turned at its lower end, and a hanger 5 in said recess.

5. In a brake head, a body portion of substantially shell formation having lugs projecting inwardly from the inner face and central holes through said lugs and holes to each 10 side of the center hole in the uppermost of said lugs and a longitudinal recess above said uppermost lug and holes through the shell to each side of said longitudinal recess, a shoe having a lug extending into the space be- 15 tween the aforesaid lugs in the head, and a central hole in alinement with the aforesaid

holes, a pin extending through said longitudinal recess and said central holes in said head and shoe lugs and a pin having a suitable head extending through one of said holes to one side of said longitudinal recess into one of the side holes in said uppermost lug and turned over at its lower end, and a hanger in said recess.

Signed at the city and district of Montreal, 25 in the Province of Quebec, in the Dominion of Canada, this 23rd day of September 1908.

JAMES McC. COLEMAN.
